[57] CLAIM

The ornamental design for a resuscitation ventilator, as shown and described.

DESCRIPTION

FIG. 1 is a perspective view of a resuscitation ventilator showing my new design;

FIG. 2 is a top plan view thereof;

FIG. 3 is a side elevation view thereof, the opposite side being a mirror image of that shown;

FIG. 4 is a right end elevation view thereof;

FIG. 5 is a left end elevation view thereof; and

FIG. 6 is a bottom plan view thereof.

FIG _ 4

FIG _ 5

FIG _ 6
